ATTORNEY

UNITED STATES PATENT OFFICE.

CHARLES W. WALKER, OF CONWAY, NEW HAMPSHIRE.

CURTAIN-ROD BRACKET.

1,408,665.

Specification of Letters Patent.

Patented Mar. 7, 1922.

Application filed May 17, 1920. Serial No. 381,984.

To all whom it may concern:

Be it known that I, CHARLES W. WALKER, a citizen of the United States, residing in the city of Conway and State of New Hampshire, have invented new and useful Improvements in Curtain-Rod Brackets, of which the following is a specification, reference being had to the accompanying drawings.

10 This invention pertains to window shade and curtain supports.

The object is to provide a simple and efficient combination window shade and curtain support which may be quickly mounted upon 15 any casing and as quickly taken down, as desired.

Another object is to provide such device in a form enabling the ready mounting of the shade or curtain, without the need of cutting off or shortening the shade roller, as is 20 ordinarily required.

In the drawings:

Figure 1 is a perspective view showing my device in use for mounting a shade and curtain pole upon a window casement.

Figure 2 is a detail showing the construction of the individual supporting element.

In carrying out the invention, I provide a combination shade roller and curtain pole 30 support indicated by the letter A. Each support is formed with an integral, outstanding hook 1 adapted to hold one end 9 of the curtain pole 2, an integral, inwardly disposed eye 3 adapted to hold one end pin

35 10 of the shade roller 4, and a plurality of integral spurs 5 which project backwardly perpendicular to the body portion 6 of the device, and are sharpened at their ends and thus adapted for readily and quickly driv-

ing into the outer face 7 of the window casement 8.

In use one such support is mounted upon each side of the casement, in horizontal alignment, and the roller and pole are then disposed between and supported by them, in 45 usual form.

While I have herein described a certain specific method of constructing and assembling the elements of my invention, it is understood same may be varied in minor details, not departing from the spirit of my invention as defined in the appended claim.

What I claim to be new and patentable is:

A combined shade and curtain fixture formed out of a single piece of material and 55 consisting of a relatively short, narrow body provided with a perforated enlargement intermediate its ends, the perforation lying directly in the longitudinal axis of said body, and adapted to receive the end of a shade 60 roller, said body having a forwardly directed curved hook at its lower end providing a recess close to said perforation for the reception of one end of a curtain pole, whereby to position the shade roller and curtain 65 pole in close relation to each other and close to the window frame, said body having a spur projecting rearwardly from its upper end whereby to secure the fixture to the window frame, the aforesaid perforated enlargement adapted to lie against the window 70 frame when the fixture is secured to said frame.

CHARLES W. WALKER.
